UNITED STATES PATENT OFFICE.

CHARLES H. GODWARD, OF ELBOW LAKE, MINNESOTA.

AUTOMOBILE CHAIN HOOK OR FASTENER.

Application filed August 11, 1923. Serial No. 656,792.

To all whom it may concern:

Be it known that I, CHARLES H. GODWARD, a citizen of the United States, residing at Elbow Lake, in the county of Grant and 5 State of Minnesota, have invented a new and useful Automobile Chain Hook or Fastener, of which the following is a specification.

This invention aims to provide a simple 10 means for tightening chains of the kind used for anti-skidding purposes on automobile tires, although the structure is not confined, necessarily, to this use. The invention aims to provide novel means for tightening the 15 chain and for holding the chain after the chain has been tightened.

It is within the province of the disclosure to improve generally and to enhance the utility of devices of that type to which the invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:

Figure 1 shows in side elevation, a device constructed in accordance with the invention; Figure 2 is a top plan; Figure 3 is a 35 side elevation wherein the device is shown in opened position; Figure 4 is a cross section on the line 4—4 of Figure 1; Figure 5 is a cross section on the line 5—5 of Figure 1; Figure 6 is a fragmental side elevation 40 showing a portion of the opposite side of the device from that which is delineated in Figure 1.

The device forming the subject matter of this application preferably is made of metal 45 throughout and includes a plate-like body 1 provided at a point adjacent to one end, and in its edge, with a seat or notch 2. Adjacent to its opposite end, the body 1 carries a securing element 3 on which is mounted pivotally one link 4 of the chain which is to be 50 tightened. The body 1 has an opening 5 located near the securing element 3. A spring latch 6 extends longitudinally of the body 1, one end of the latch being secured, as at 7 55 to the body 1. Adjacent to its free end, the

latch 6 is curved away from the body as indicated at 8 and terminates in a transverse arm 9 extended through the opening 5 in the body 1, the arm 9 being provided with an operating button 10.

The device comprises a lever 11, which is H-shaped in top plan, as shown in Figure 2, and of angular form in side elevation, as disclosed in Figure 1. At one end, the lever 11 terminates in spaced fingers 12, between which one end of the body 1 is received, a pivot element 14 uniting the fingers 12 with the body. At its opposite end, the lever 11 has arms 15 and 16, spaced apart transversely and disposed at an angle to the main portion of the lever. The arm 15 terminates in an outstanding keeper 17 the arm being beveled as at 19 outwardly of the keeper. The arm 16 terminates in a hook 18 extended parallel to the body 1.

When the device is opened as shown in Figure 3, a link 20 of the chain which is to be tightened is mounted on the arms 15 and 16 of the lever, the hook 18 on the arm 16 aiding in retaining the link 20 on the lever. 80 When the lever 7 is swung to the closed position shown in Figure 1, the link 20 is advanced and is lodged in the seat 2 of the body 1. The arms 15 and 16 of the lever 11 are located on opposite sides of the body 1, when the device is closed, the beveled end 19 of the arm 15 facilitating the passage of the arm 15 between the spring latch 6 and the body 1, the keeper or shoulder 17 on the arm 15 engaging the latch 6 to hold the lever 11 85 in the position shown in Figure 1. When it is desired to swing the lever 11 into the open position of Figure 3, pressure is exerted on the button 10 of the latch 6, the arm 9 of the latch moving in the opening 5 of the body 1 and the latch being disengaged from the keeper 7 on the arm 15 of the lever 11. It is to be observed that when the structure is closed, as shown in Figure 1, one link 4 of the chain is connected to the body 1 by the securing element 3, the other link 20 of the chain being lodged in the seat 2 of the body 1. Consequently, all of the tensile strain 90 comes on the body 1 and the lever 11 serves, merely, to hold the link 20 engaged with the seat 2.

What is claimed is:

A chain fastener including a body portion having a seat, a lever pivoted to the body portion and constituting a closure for 110

the seat, said lever having an outstanding keeper, a spring arm forming a latch secured to the body and extending longitudinally of the body, said spring arm adapted to coact with the outstanding keeper to hold the lever in closed position with respect to the seat, said latch having an arm, the body having an opening through which the arm extends, and a button on the free end of the last mentioned arm to be engaged by the finger of the

operator for disengaging the latch and keeper.

In testimony that I claim the foregoing as my own, I have hereto affixed my signature in the presence of two witnesses.

CHARLES H. GODWARD.
